UNITED STATES PATENT OFFICE.

SAMUEL COURTIÉR ABBEY, OF NEW YORK, N. Y., ASSIGNOR OF ONE-THIRD TO EDWARD REILLY AND ONE-THIRD TO WILLIAM J. REYNOLDS, BOTH OF NEW YORK, N. Y.

DESIGN FOR AN INDIVIDUAL FRYING PAN.

Application filed March 6, 1924. Serial No. 8,861. Term of patent 3½ years.

To all whom it may concern:

Be it known that I, SAMUEL COURTIÉR ABBEY, a citizen of the United States, and a resident of the city of New York, borough of Manhattan, in the county and State of New York, have invented a new, original, and ornamental Design for an Individual Frying Pan, of which the following is a specification, reference being had to the accompanying drawing, forming part thereof.

I claim:
The ornamental design for an individual frying pan, as shown.

SAMUEL COURTIÉR ABBEY.
